UNITED STATES PATENT OFFICE

JOSEPH KRELL, OF BERLIN-ZEHLENDORF, GERMANY

SAFETY APPLIANCE

Application filed April 25, 1929, Serial No. 358,079, and in Germany May 3, 1928.

My invention relates to printing machines, such as machines for printing addresses and the like, and more particularly to a safety appliance for such machines, and it is an object of my invention to provide a simple and reliable safety appliance which will not interfere with the operation of the machine and not require the machine to be stopped.

To this end I provide a guard adapted to engage the fingers of an operator, and I so control this guard that it projects into the path of the head when the head is raised, and is moved out of its path and toward the operator's station when the head descends.

Preferably the means for controlling the guard are operatively connected with the printing head.

My novel safety appliance engages with absolute reliability any number of fingers which may be in the danger zone, and pushes them back so that they are not struck by the descending head. At the same time it is not necessary to stop the machine to prevent the head from engaging a finger.

In reducing my invention to practice I provide a guard which in its initial position projects to a short distance above the table of the machine so as to admit a paper or form on which the machine prints but not the operator's fingers, and upon descent of the printing head is moved out of the path of the head toward the front, that is, toward the operator's station, and pushes back any finger that may be in its way. Preferably the guard is made of rubber or other resilient material and is arched on its lower face so that the lower part of the arched face approaches the table of the machine and the guard performs a sort of rolling movement with respect to the table, pushing back the fingers at considerable force.

In a preferred embodiment of my invention I provide an arm of comparatively short length which is fulcrumed on the printing head and a link fulcrumed on the frame of the machine and pivotally connected with the arm so that the connection of the link and the arm moves on an arc of a circle about the fulcrum of the link. This fulcrum is preferably arranged above and a short distance in front of the fulcrum of the arm on

the head so that an upward movement is imparted to the guard which is attached to the free end of the arm immediately upon the descent of the printing head.

It is another object of my invention to adapt the guard to printing pads of various widths and to this end I provide means for displacing the fulcrum of the link on the frame of the machine.

It is still another object of my invention to render the guard inactive when the machine is cleaned or inspected and to this end I provide means for fixing the guard in such inactive position.

I shall now describe my invention with reference to a machine having a rocking printing head but it is understood that it may also be applied to a machine having a head guided on a vertical line and not on a curve, and that it makes no difference whether the printing head is provided with a printing pad as will be described, or with type for printing.

In the accompanying drawings a machine having a rocking printing head and equipped with my novel safety appliance is illustrated by way of example.

In the drawings

Fig. 1 is an elevation of the machine viewed from the front or the operator's station,

Fig. 2 is a plan view of the machine, the arrow "I" indicating the direction in which the machine is viewed in Fig. 1,

Figs. 3 and 4 are end elevations viewed in the direction of the arrow "III" in Fig. 2, and showing the printing head raised and lowered, respectively, with the control set for a narrow printing pad,

Figs. 5 and 6 are similar illustrations showing the control set for a wider printing pad, Fig. 7 shows the guard in inactive position, Fig. 8 is a detail illustration showing the means for fixing the link in inactive position, and viewed in the direction "VIII", Fig. 7, and

Fig. 9 is a detail illustration, drawn to a larger scale and showing the means for fixing the guard in inactive position.

Referring now to the drawings, 1 is the frame of the machine, 2 is its table, 3 is a

guideway in the table for feeding printing plates 4 to the printing station, 5 is a supply hopper for the printing plates, 6 is the printing station, 7 is a ribbon moved above the printing plates, 8 is a printing arm pivotally carried on the table 2, 10 is the printing head, 11 is a printing pad on the head, and 11' is a rubber plate on the lower face of the pad 11. Forms or other papers to be printed are placed on top of the ribbon 7 and forced down onto the printing plates 4 by the pad 11.

12 is a substantially U-shaped bracket having two rearwardly extending arms 12' and secured to the front face of the printing head 10, 13 is a pivot in each arm, 14 are arms pivoted on the pivots 13, 15 is a guard secured to the free ends of the arms 14, 16, Fig. 1, is a curved link which engages one of the arms 14 by a pivot 14', 16' is a boss at the end of the link 16, 17' is a pin about which the link is adapted to rock and on which it may be displaced as will be described, 16" is a projection on the boss opposite the link 16, 17 is a boss at the upper end of an upright 18 which may be secured to the hopper 5, 19 and 20 are holes in the boss 17 for the reception of the pin 17', and 21 is a set screw for holding the pin in the hole 19.

As shown for a narrow printing pad in Figs. 3 and 4, the pin 17' is inserted in the hole 19, and held by the set screw 21 in which position the pin 17' is at a considerable distance above the pivots 13 of the arms 14, 14, and some distance in front of such pivots. The effective length of the link 16 is such that with the printing head raised as in Fig. 3 the guard 15 does not depend vertically from the pivots 13 but is moved a little to the front from such vertical position.

Referring now to Figs. 5 and 6 these show the printing head 10 equipped with a wider pad 11a. In this case a bracket 12' is provided in which the pivots 13' are further to the front than in the example illustrated in Figs. 3 and 4 and the pin 17' for the link 16 is inserted in the hole 20 instead of the hole 19, and held by the set screw 21.

The lower face of the guard 15 is arched upwards, and so is its rear end. The radius of the arch is such that when the guard moves from the position Fig. 3 into the position Fig. 4 the vertical clearance between the table 2 and the lowest point of the guard 15 is very small for any position of the guard.

Referring now to Fig. 9, 24 is a bolt in the bracket 12 which is urged out of its bore by a spring 23, and adapted to engage in a hole 25 of one of the arms 14, for an object which will be described.

Before starting for a printing operation the parts are in the position illustrated in Fig. 3 in which the guard 15 hangs down into the path of the printing head 10. In this position it does not interfere with the introduction of a form or the like but retains the fin-

gers of the operator. When the printing head 10 descends into printing position the guard 15 is moved toward the front and into the position Fig. 4 in which it is moved out of the path of the printing head 10. In this position it permits the pad 11 to engage the form on the ribbon 7. When the printing arm 8 is raised again the guard is returned to the position Fig. 3 by the link 16 and the arms 14. If now the operator upon downward movement of the arm 8 does not remove his fingers out of the path of the printing head 10, as shown in Fig. 3, the guard 15 upon descent of the printing head and as shown in Fig. 4, pushes back the fingers without hurting them as the guard is of resilient material. Nor can the fingers be caught between the guard 15 and the table 2. If desired the guard 15 might be provided with an outwardly curved extension, not shown, which before the guard 15 has completed its outward stroke will assist in pushing back the fingers and still more reliably prevent jamming of the fingers between the guard and the table.

The guard must not interfere with certain operations, such as, for instance, exchanging the pad 11 or 11a, inserting a new ribbon 7, etc. Referring to Figs. 7, 8, and 9, the link 16 with its boss 16' is displaced axially on the pin 17' in the direction "22", Fig. 1, until the link has released the pin 14', whereupon the link is thrown over into the position Figs. 7 and 8 and moved in the direction "22" until the end of the boss 16' engages the boss 18 and the projection 16" comes to bear on the top of the boss 18, preventing unintentional return of the link 16. After the pin 14' has been released by the link 16 the arms 14 of the guard 15 are turned up until the spring catch 24 engages in the hole 25, holding the guard in the position Fig. 7.

I claim:

1. A safety appliance for address printing or similar printing machines with a printing head moving up and down, for preventing the nipping of the operator's fingers by the descending printing head, comprising in combination a protective body, means for hanging the body in the path of the printing head when the printing head is raised, means pivotally suspended from a stationary part of the machine and pivotally connected to the hanging means for controlling the body so that during the down stroke of the printing head the body is rocked forwards, that is towards the person in charge and out of the path of the printing head.

2. A safety appliance as claimed in claim 1 wherein the means for hanging the body from the printing head consists of comparatively short arms and the means for controlling the movement during the down stroke of the head includes a substantially long guiding link the upper end of which is rotatably supported in the frame of the machine so

as to swing in a circular arc about the axis of rotation of the said link.

3. A safety appliance as claimed in claim 1 wherein the means for controlling the movement of the body includes a substantially long guiding link operatively connected at the lower end to the means for hanging the body and having its upper end pivotally connected to the frame of the machine above 10 and a short distance in front of the axis of the hanging means so that from the commencement of the downward movement of the printing head an upward rocking movement of the protective body is effected about 15 the pivot by which it is secured to the printing head.

4. A safety appliance as claimed in claim 1 wherein a block is carried by the printing machine above and forwardly of the printing 20 head and wherein the means for controlling the movement of the protective body includes a link, the upper end of which is pivotally and adjustably connected in the longitudinal direction to the block, a projecting nose extending from the upper connected end of the link, the opposite end of the link being releasably and operatively connected to the means for hanging the body to the head, the nose being arranged so that after the release 25 of the connection between the link and the hanging means the link can be rocked about its pivot out of its working position and displaced in the longitudinal direction of its upper pivoted end and fixed in an inoperative 30 position with the nose upon the supporting block.

5. A safety appliance as claimed in claim 1, wherein a spring bolt is mounted on the 40 printing head, the end of the bolt normally projecting slightly outwardly and wherein the means for angularly suspending the body includes pivoted arms, one of said arms being provided with an aperture for receiving the spring bolt at the time the device is moved 45 to inoperative position.

6. A safety appliance as claimed in claim 1, wherein the means for hanging the body to the head includes pivoted arms and the 50 means for guiding the body includes a link the lower end of which is pivoted to the arms, a block carried with the machine and provided with two holes located side by side for receiving the upper pivot of the link, one of 55 the holes being used when employing broad printing pads and the other holes being used when employing narrow printing pads, substantially as and for the purposes set forth.

7. A safety appliance as claimed in claim 1 60 wherein the protective body consists of a piece of resilient material having the bottom surface of relatively considerable breadth of the direction of swing and so curved that when the printing body rocks 65 out of the path of the printing head the rear

portion of the bottom surface of the protective body continually approaches the table of the machine.

In testimony whereof I affix my signature.
